UNITED STATES PATENT OFFICE.

EDWARD L. O'CONNOR, OF NEW YORK, N. Y.

ARTIFICIAL HAND.

1,277,747.

Specification of Letters Patent.

Patented Sept. 3, 1918.

Application filed May 24, 1917. Serial No. 170,592.

To all whom it may concern:

Be it known that I, EDWARD L. O'CONNOR, a citizen of the United States, residing at New York, in the county and State of New York, have invented certain new and useful 5 Improvements in Artificial Hands, of which the following is a full, clear, and exact description.

This invention relates to artificial hands, 10 and its chief object is to provide a jointed hand of which the thumb and fingers can be flexed at the will of the wearer whereby certain movements and functions of the natural hand can be usefully reproduced. To this 15 and other ends the invention consists in the novel features of construction and combinations of parts hereinafter described and set forth in the claims.

In its preferred form the invention comprises 20 a socket member adapted to be fitted upon the stump of the forearm, and a band or corset for the upper arm, the two parts being jointed together to permit flexure of the stump and socket-member of the muscles 25 of the upper arm. The thumb and fingers of the hand are jointed, and connection is provided between the mechanism of the hand and the arm-band or corset whereby flexure of the fore-arm stump and socket 30 member will flex the fingers and thumb.

One form of the invention is illustrated in the annexed drawings; in which—

Figure 1 is a perspective view showing the hand fitted to the person of the user.

Fig. 2 is a plan view of the complete hand.

Fig. 3 is a sectional plan view of the socket-member and arm-band, showing also the frame of the hand proper.

Figs. 4 and 5 are detail cross sections on 40 lines 4—4 and 5—5, respectively, of Fig. 3.

Fig. 6 is a detail side view of the hand-mechanism, and

Fig. 7 is a plan view of the same.

Fig. 8 is a horizontal section on line 8—8 45 of Fig. 7.

The socket-member 10, adapted to be fitted to the stump of the forearm, comprises a sleeve 11 of canvas, leather, or other suitable material, made in two parts laced together 50 at front and rear along a longitudinal line so as to be capable of adjustment according to the thickness of the stump on which it is to be fitted. The two parts are securely fastened (as by rivets) to a pair of longitudi-

nal side members 12, which are themselves 55 secured at their outer ends to a wrist-block 13, which latter is also surrounded by the sleeve 11, as shown in Figs. 2 and 3. At their inner ends the braces or side-members 12 are provided with longitudinally slotted 60 parts 14 connected to the main portions of the braces by screws 15 extending through the slots, as clearly shown in Fig. 3. The upper-arm band or corset 16 is made of similar material to the socket-member sleeve, 65 and is also made in two parts with front and rear lacings, to fit arms of different sizes. It is also provided with longitudinal braces or side-members 17, which are pivotally jointed at 18, to the adjacent ends of 70 the side-members 12—14 so that the arm can be bent at the elbow. The sliding connection of the parts 12 and 14 permits the joints 18 to be brought in alinement with, or sufficiently close to, the axis of the elbow to 75 permit easy flexure of the arm at that point. Socket-members and arm-bands of a standard size can thus be used with stumps of different lengths, as will be readily understood.

The wrist-block 13 carries an outwardly extending wrist-bar 19, and integral therewith at its outer end are two aligned and axially spaced wrist-bearings 20, 21, having, 80 near their outer ends, a pair of longitudinally extending arms 22, 23, terminating in knuckle-bearings 24, 25. These parts comprise what for convenience may be termed the frame of the hand proper, the arms 22, 23 performing the functions of the metacarpal bones of the natural hand. The parts 19, 20—21 and 22—23, can be conveniently 85 termed the wrist-member.

The wrist-shaft 26, Figs. 6, 7 and 8, is mounted in the wrist-bearings 20, 21, and 90 pinned to it at one end, outside the adjacent bearing, is a thumb-member 27, which is fastened on the wrist-shaft at an appropriate side of the bar 19 and is curved to approximately the form of a partly flexed 100 natural thumb. Secured to the thumb member near the wrist-shaft 26, and extending across the "palm" of the hand above the plane of the bearings 20—21 and 24—25, 105 and parallel to the wrist-shaft, is a finger-actuating rod 28, connected to the wrist-pin by means of a link 29 pinned thereto. The latter is arranged between the two

wrist-bearings 20, 21, and is provided with an eye 30 for connection with the forward or outer end of a cord or "ligament" 31, the rear or inner end of which is connected to a ring 32, Figs. 1 and 2, which is itself connected by diverging straps 33 to the side members 17 of the arm-band. It will therefore be seen that when the arm is straightened the ligament exerts a pull on the link 29, thereby rocking the wrist-shaft 26 and swinging the thumb-member 27 toward the dotted line position shown in Fig. 6. Preferably the ligament 31 is of such length that the pull on the link 29 will occur just before the arm is straightened to the fullest extent, but the ligament is adjustable as to length by untying one or both knots at the ends and drawing it up or letting it out, so that the user can regulate the actuation of the hand-mechanism to suit himself. An adjustable strap 34 around the upper arm and over the ligament-branches 33 prevents too great slackness of the ligament when the arm is bent.

25 The knuckle-joint of the fingers is formed by the knuckle-bearings 24, 25, and a knuckle-shaft 35 mounted therein, on which the basilar phalanges 36 are rigidly mounted. The knuckle-shaft 35 is also equipped with a lug 37, extending oppositely from the fingers and connected by a link 38 to the finger-actuating rod or pin 28, so that as the thumb-member is swung toward the dotted line position of Fig. 6 by the pull of the ligament 31, as already described, the knuckle shaft will be rocked and the fingers thereby extended. In short, the pull of the ligament, exerted by straightening the arm, opens the hand. A coil spring 39, connected to the eye 30 on link 29, and to an eye 40 on the knuckle-shaft 35, aided by a U-spring 41 connected to the thumb-member 27 and to the basilar phalanx of the first or index finger, opposes the described opening movement and hence serves to swing the thumb and fingers toward a closed position of the hand when the arm is bent at the elbow and the pull on the ligament thereby relaxed. Either spring may be omitted if desired, but

50 I prefer to have both, as in that case the breakage or failure of one spring will still leave the hand operative.

Each basilar phalanx of the fingers is hollow or tubular and carries a sliding pawl 42, Fig. 8, urged outwardly by a coil spring 43 and co-operating at its outer end with ratchet teeth on the inner end of the middle phalanx, so as to hold the latter in any one of several positions of flexure, as will be

55 clearly understood from Fig. 8. The inner or palm ends of the pawls 42 are connected to links 44 which are slotted longitudinally at their other ends to engage the finger-actuating rod or pin 28. When the parts are

60 in the positions shown in Fig. 8 the bar 28

is at the forward end of this slot. As the link 29 is rocked counterclockwise by the pull of the ligament 31 to "open" the hand the bar 28 approaches the rear end of the slot; and just before the arm fully straightens (and the thumb and basilar phalanges thereby straighten to the fullest extent) the bar reaches the rear end of the slot. Further straightening of the arm then causes the bar to draw the links 44 rearwardly, thereby retracting the pawls 42 and releasing the middle phalanges, as will be readily understood. The elastics 45 then contract and swing the middle phalanges out into alignment with the basilar phalanges. Preferably the slots in the links 44 are successively longer from the index finger to the little finger, so that straightening the arm will permit the index finger to straighten first, then the middle finger, ring finger and little finger in succession, as will be readily understood. When the arm is flexed again the springs 43 restore the pawls to their outer positions, whereupon the user can, with his other hand, flex any or all of the middle phalanges, the pawls instantly locking them at each of their several positions of flexure. The elastics 45 can be ordinary rubber bands or small coil springs. Preferably their ends are attached to small hooks 46 so that the user can replace them in case of breakage or can omit them entirely. In the latter case the fingers are straightened by the user's other hand, or, if the joints are sufficiently loose, they can be thrown out straight by a quick movement of the arm. The outermost or ungual phalanges of the fingers are flexed and straightened by the other hand, and preferably work a little stiffly so that they will stay in bent position.

105 The mechanism of the hand is covered with felt or other suitable material 47, Fig. 2, the finger-coverings being slotted down the backs (not shown) to afford access to the finger-springs 45, Figs. 7 and 8. A glove is worn over the whole, as is customary. As the user walks along the street, with his arm hanging down at his side and the tips of the fingers slightly bent, he can, by an almost imperceptible movement of the elbow joint, open or close the hand in a very natural manner, so that the ordinary observer will scarcely notice that the hand is not the natural member.

110 The arm-band 16 should be loose enough to permit free extension and contraction of the arm muscles. A shoulder harness 48, of any convenient and suitable character, is provided to hold the arm-band and socket-member in proper position, thus permitting a heavy load to be carried when the arm is extended downwardly at the side of the user's body; it being understood that in such case the arm is held bent at the elbow just enough to keep the fingers locked in bent 115 120 125 130

position. Hand baggage, and other articles, can thus be carried almost as conveniently and easily as with the natural hand.

It is to be understood that the invention 5 is not limited to the construction herein specifically illustrated and described, but can be embodied in other forms without departure from its spirit as defined by the appended claims.

10 I claim:

1. In an artificial hand, in combination, a wrist member having wrist-bearings and arms provided at their ends with knuckle-bearings for a knuckle-joint, a thumb-member 15 fixed to the wrist-shaft, a wrist-shaft mounted in the wrist-bearings, a finger-actuating pin mounted on the thumb-member adjacent to the wrist-bearings and extending across the palm of the hand, a knuckle-shaft mounted in the knuckle-bearings and connected to the finger-actuating pin to be rocked thereby, fingers carried by the knuckle-shaft, means for mounting the hand upon the stump of the forearm, and 20 means for connecting the wrist-shaft with the upper-arm of the user whereby flexure of the arm at the elbow will rock the wrist-pin and the knuckle-shaft.

2. In an artificial hand, in combination, a 25 wrist-member, a thumb-member pivoted on the wrist-member, fingers pivotally carried by the wrist-member, a finger-actuating pin extending from the thumb-member across the palm of the hand, a finger-actuating arm 30 extending from the axis of the fingers rearwardly and downwardly below the palm of the hand, a link connecting the said arm with the said pin whereby upward rocking of the thumb-member will swing the fingers 35 toward the plane of the palm, means for connecting the said pin to the upper-arm of the user whereby straightening the arm at the elbow will rock the thumb-member upwardly, and means for swinging the 40 thumb-member and the fingers toward each other when the arm is bent at the elbow.

3. In an artificial hand, in combination, a 45 wrist-member having knuckle-bearings for a knuckle-joint, a thumb-member pivoted on the wrist-member, a rock-shaft in said knuckle-bearings, fingers fixed to said shaft and having jointed phalanges, the middle phalanges being capable of flexure on the basilar phalanges independently of 50 each other, devices coöperating with the middle phalanges to lock the same in bent position independently of each other, and mechanism for shifting the locking devices to release the middle phalanges and permit 55 the same to swing toward alinement with the basilar phalanges.

4. In an artificial hand, in combination, 60 fingers having flexibly jointed phalanges, devices carried by the basilar phalanges and 65 coöperating singly with the middle pha-

langes to positively lock the same against straightening movement when bent, and mechanism adapted to be connected with the upper-arm of the user and actuated by straightening the arm at the elbow to shift 70 the locking devices out of engagement with the middle phalanges to permit straightening of the same.

5. In an artificial hand, in combination, 75 fingers having flexibly jointed phalanges, devices carried by the basilar phalanges and slidable longitudinally and coöperating with the middle phalanges to lock the latter in bent position, yielding means for shifting the locking devices into engagement with the 80 middle phalanges, means for retracting the locking devices to permit straightening movement of the middle phalanges, and means for connecting the retracting means to the upper-arm of the user for actuation 85 by straightening the arm at the elbow.

6. In an artificial hand, in combination, a 90 finger having flexibly jointed phalanges, the middle phalanx having ratchet-teeth on its inner end, a spring-actuated sliding pawl carried by the basilar phalanx and coöperating with said ratchet teeth to hold the middle phalanx in any of several bent positions, means adapted for connection with the upper-arm of the user to retract the pawl 95 when the arm is straightened at the elbow, and yielding means to swing the middle phalanx toward alinement with the basilar phalanx when said pawl is retracted.

7. In an artificial hand, in combination, 100 fingers having a flexible knuckle-joint and flexibly jointed phalanges, mechanism adapted for connection with the upper-arm of the user and actuated by straightening the arm at the elbow to swing the basilar phalanges at the knuckle-joint toward alinement with the palm of the hand, devices engaging the middle phalanges to lock the same in bent position, and means connecting the said devices to the aforesaid mechanism for actuation thereby to unlock the middle phalanges, whereby the latter may be swung toward alinement with the basilar phalanges when the arm is straightened at the elbow.

8. In an artificial hand, in combination, a 110 wrist-member having supports for a knuckle-joint, a rock-shaft mounted in said supports, fingers fixed on said shaft and having flexibly jointed phalanges, a thumb-member pivoted on the wrist-member, a finger-actuating pin extending from the thumb-member across the palm of the hand and connected with the aforesaid rock shaft to cause the thumb-member and the shaft with the fingers thereon to swing simultaneously but in 115 opposite directions, devices movably carried by the basilar phalanges of the fingers and yieldingly urged into engagement with the inner ends of the middle phalanges to hold the latter in bent position, links connected 120

125 130

at their forward ends with the said devices to shift the same out of locking engagement with the middle phalanges and thereby permit the same to swing toward alinement 5 with the basilar phalanges, said links having their rear ends provided with slots engaging the aforesaid pin, and means adapted for connection with the upper-arm of the user to swing said pin about the axis of the 10 thumb-member when the arm is straightened at the elbow, whereby such straightening movement of the arm swings the thumb-member and the fingers away from each other and unlocks the middle phalanges of 15 the fingers.

9. In an artificial hand, in combination, fingers having flexibly jointed phalanges, devices coöperating with the middle phalanges singly to lock the same against straightening when in bent position, and mechanism 20 adapted to be connected with the upper arm of the user and actuated by straightening the arm at the elbow to release the locking devices from the middle phalanges, said mechanism including links, having slots of 25 different lengths coöperating with said locking devices for causing the same to be released in succession.

In testimony whereof I affix my signature.

EDWARD L. O'CONNOR.
